United States Patent Office

Des. 187,519
Patented Mar. 29, 1960

187,519

HAT

Hyman B. Lasting, Portsmouth, Va.

Application May 11, 1959, Serial No. 55,864

Term of patent 7 years

(Cl. D3—13)

FIG. 1

FIG. 2

Figure 1 is a side perspective view of a hat showing my new design, the side opposite thereto being identical in appearance; and

I claim:

The ornamental design for a hat, as shown and described.
